(57) **CLAIM**

We claim the ornamental design for a wild bird feeder, as shown and described.

DESCRIPTION

FIG. 1 is a side perspective view of a wild bird feeder showing the new design thereof;

FIG. 2 is an exploded side perspective view of the wild bird feeder with portions detached;

FIG. 3 is a top side elevational view of the wild bird feeder thereof;

FIG. 4 is a front side elevational view, taken along line 4-4 of FIG. 3, of the wild bird feeder thereof;

FIG. 5 is a back side elevational view, taken along line 5-5 of FIG. 3, of the wild bird feeder thereof; and,

FIG. 6 is a side perspective view, taken along line 6-6 of FIG. 3, of the wild bird feeder thereof.

The broken line portions are not claimed.
